UNITED STATES PATENT OFFICE

171,804

IMMERSION HEATER

Fredrick L. Lefebvre, Twinsburg, Ohio

Application February 18, 1953, Serial No. 23,674

Term of patent 3½ years

(Cl. D81—10)

To all whom it may concern:

Be it known that I, Fredrick L. Lefebvre, a citizen of the United States and resident of Twinsburg, State of Ohio, have invented a new, original, and ornamental Design for an Immersion Heater, of which the following is a specification, reference being had to the accompanying drawing, forming a part hereof.

Figure 1 of the drawing is a side elevation of an immersion heater, showing my new design;

Figure 2 is a front elevation of the same;

Figure 3 is a bottom end view of the immersion heater shown in Figure 1; and

Figure 4 is a top plan view of the immersion heater shown in Figure 1.

I claim:

The ornamental design for an immersion heater, as shown.

FREDRICK L. LEFEBVRE.
